UNITED STATES PATENT OFFICE.

BENJAMIN G. GILBOUGH, OF CHICAGO, ILLINOIS, ASSIGNOR TO METAL SPECIALTIES MANUFACTURING COMPANY, OF CHICAGO, ILLINOIS, A CORPORATION OF ILLINOIS.

LAMP-BRACKET.

1,044,772.

Specification of Letters Patent.

Patented Nov. 19, 1912.

Application filed April 14, 1910. Serial No. 555,368.

To all whom it may concern:

Be it known that I, BENJAMIN G. GILBOUGH, a citizen of the United States, residing at Chicago, in the county of Cook and State of Illinois, have invented a new and useful Improvement in Lamp-Brackets, of which the following is a specification.

My invention relates particularly to brackets adapted to serve as a means for mounting electric lamp sockets on the burners of oil and gas lamps, thus providing convertible lamps, for use in either form, according to desire or necessity.

My primary object is to provide a simple and inexpensive bracket of the character indicated which will serve to support an electric bulb in close relation to the burner of an oil-lamp or gas-lamp, so that the electric bulb will be properly located with reference to the reflector, and which will permit the electric bulb to be turned from its standing position adjacent the original burner when it is desired to use the original burner, thus rendering it unnecessary to disconnect the electric lamp from said burner at such time.

The invention is illustrated in its preferred embodiment in the accompanying drawing, in which—

Figure 1 represents an electric bulb and socket mounted upon the burner-cap (shown in dotted lines) of an oil-lamp through the medium of my improved bracket, or mounting; Fig. 2, a plan view of the improved bracket; Fig. 3, an elevational view of the same; Fig. 4, a section taken as indicated at line 4 of Fig. 3; and Fig. 5, a perspective view of a gas-burner equipped with my device, slightly modified, serving as a mounting for an electric light.

In the preferred construction, which is illustrated, the invention comprises a burner-clip, or burner-clamp, A; and a socket-clip, or socket-clamp, B, angularly adjustable with relation to the clip A. The clamp A preferably is a spring-clamp, in the form of a split ring of resilient metal, having a vertical axis, and adapted to be slipped onto the burner-cap 1 from above; and the clamp B, also, is preferably a spring-clamp, employing a split-ring having a vertical axis and into which the electric light socket 2 may be slipped.

The split-ring A is formed of sheet-metal, and has a flattened circular base-portion, or pivotal-head, 3 with curved arms 4 extend-

ing therefrom, said arms split to render them more springy in applying the clamp. The head 3 is formed by striking the metal outwardly to form a flat boss on the convex side of the central portion of the split-ring. 60

The socket-clamp B preferably comprises a shank 5 having a pivotal head 6 and carrying a split-ring 7 projecting at right angles to the plane of the head 6. The pivotal heads are joined by a horizontally-disposed central pivotal rivet 8, which holds the members close together, the split-rings being placed virtually back to back. The member B may be conveniently formed from sheet metal. The disk-form head 6 is 70 provided with a lower-edge locking-notch 9, and two diametrically opposite lateral-edge locking-notches 10. The head 3 is provided near its lower edge with an outwardly-struck locking-lug, or projection, 11, 75 adapted to engage the central (lower) locking-notch 9 when the electric lamp is in the standing position and adapted to engage one or the other of the lateral-edge notches 10 when the member B is rotated through 80 an angle of 90 degrees, according to direction of rotation. Between the lower, or central, notch 9 and the two lateral notches 10, the metal forms segments 12, carried by arms 13 which taper from the center of the 85 disk to their points of junction with said segments at their centers: that is to say, the metal is cut away, as indicated at the points 14, to form said arms and segments.

In the modification shown in Fig. 5, I 90 employ the same socket-clamp B in connection with a slightly modified burner or burner-tube clamp A¹. The construction is the same as that already described and the parts are similarly lettered, except where 95 modified. The clamp A¹ has a burner-tube embracing-ring 15 provided with ears 16 joined by a clamp-bolt 17. The ring 15 carries an upturned shank 18 having a head 3^a which corresponds with the head 3 of 100 the previously-described construction. The socket clamp B has its pivotal head 6 joined to the head 3^a by the pivot 8, and the pivotal heads are provided with the same catch-devices employed in the previously-described construction. The burner-tube clamp A¹ may be of integral formation, being conveniently formed from metal. 105

The manner of use may be briefly described. When it is desired to employ an 110

electric light in connection with an oil lamp, the mounting shown in Figs. 1 to 4 inclusive is employed, and it is only necessary to slip the burner-clamp A onto the burner-cap 1 and slip the electric light socket into the clamp B, the parts being so adjusted that the electric lamp will be exposed just in the rear of the burner-cap (or if preferred in front of the burner-cap). When it becomes 5 desirable or necessary to employ the oil-burner, the clamping member B may be turned about its horizontal pivot, say, through an angle of 90 degrees, until one of the lateral locking notches 10 engages the locking lug 11. It will be understood that 10 during the operation of turning the electric light from its standing position to its horizontal position, and vice versa, the segment engaged by the projection 11 and the arm carrying said segment will yield, the projection 11 being rounded or beveled to permit 15 it to be disengaged from the locking notch when force is applied. When it is desired to employ an electric light in connection 20 with a gas-burner, the mounting shown in Fig. 5 is employed, and the manner of use 25 is similar to that already described.

The construction described is exceedingly simple, may be cheaply manufactured, is 30 thoroughly durable and is also thoroughly effective for its purpose.

The foregoing detailed description has been given for clearness of understanding only and no undue limitation should be understood therefrom, but the appended claims are to be construed as broadly as permissible in view of the prior art.

What I regard as new, and desire to secure by Letters Patent, is—

40 1. A mounting for the purpose set forth, comprising a burner-clamp and a socket-clamp secured thereto by a horizontal pivot extending toward the axis of said burner-clamp, whereby an electric light socket carried by said socket-clamp may be held in standing position or may be turned laterally to a horizontal position.

45 2. A mounting of the character set forth, comprising a clamp adapted to be applied to a lamp-burner, said clamp provided with a transversely disposed pivotal head, a socket-clamp provided with a transversely disposed pivotal head, a pivot extending toward the axis of the burner-clamp and 50 securing said heads together, and catch-devices carried by said pivotal heads.

3. A mounting of the character set forth, comprising a clamp adapted to be applied to a lamp-burner, said clamp provided with a pivotal transversely disposed head, a 60 socket-clamp provided with a pivotal transversely disposed head, and a horizontal pivot-rivet extending toward the axis of the burner-clamp and securely joining said heads together, said heads being provided 65 with lug and notch connections permitting angular adjustment of one clamp with relation to the other.

4. A device of the character set forth, comprising a clamp adapted to be applied to 70 a lamp-burner and equipped with a pivotal head having an outwardly-struck locking-lug, a socket-clamp having a pivotal head provided with a plurality of peripheral locking notches, and a pivot joining said 75 heads together.

5. A device of the character set forth, comprising a burner-embracing ring and a socket-embracing ring equipped with pivotal heads and placed back to back, a horizontal pivot joining said pivotal heads closely together, and catch-devices carried by said pivotal heads adapted to secure the heads in different positions of angular adjustment.

85 6. A device of the character set forth, comprising a burner-clamp and a socket-clamp equipped with pivotal heads, one of said heads having a locking lug, and the other of said heads having resilient arms 90 carrying segments with notches at their ends adapted to receive said locking lug.

7. A device of the character set forth, comprising a spring-clamping ring adapted to embrace a burner-cap and having an outwardly-struck pivotal transversely disposed head, and a socket-clamp having a split socket-engaging ring and a pivotal transversely disposed head joined to said first-named pivotal head by a horizontal pivot 100 which extends toward the axis of the burner-clamp.

8. A mounting of the character set forth, comprising a burner-clamp having a pivotal head, in combination with a socket-clamp 105 having a pivotal head swiveled on said first-named pivotal head, the swiveling axis being radial with relation to the burner clamp.

BENJAMIN G. GILBOUGH.
